UNITED STATES PATENT OFFICE.

GUSTAVE M. GOLDSMITH AND CARL BARTELS, OF HAMILTON, OHIO, ASSIGNEES TO
THE MOSLER SAFE COMPANY, OF HAMILTON, OHIO, A CORPORATION OF NEW
YORK.

SAFE CONSTRUCTION.

Application filed February 5, 1924. Serial No. 690,723.

To all whom it may concern:

Be it known that we, GUSTAVE M. GOLDSMITH and CARL BARTELS, citizens of the United States, residing at Hamilton, in the county of Butler and State of Ohio, have invented certain new and useful Improvements in Safe Construction, of which the following is a specification.

This invention relates to safe construction, and more particularly relates to burglar-proof safe doors and vestibules made up of a plurality of plates or sections secured together, one or more of the plates or sections having special characteristics, such as being highly resistant to drills, or to torches, or the like; and the principal object of our invention is to provide a construction for safe doors and vestibules in which these plates and sections are secured and held together in such a way that the structure is thoroughly proof against penetration and entry by means of a torch or drill, or the like, and in which the plates or sections are held against bodily removal under attack. Another object of our invention is to eliminate the necessity of relying upon screws to hold the sections or plates together. A further object of our invention is to provide a safe door and vestibule construction in which material having special characteristics, such as being highly resistant to drills, torches, or the like, is so incorporated that it is substantially co-extensive with the door or vestibule, in the plane thereof, and cannot be removed therefrom or displaced. Other objects of our invention will be in part obvious and in part pointed out hereinafter.

In order that a clearer understanding of our invention may be had attention is hereby directed to the accompanying drawings, forming a part of this application, and illustrating certain possible embodiments of our invention.

Referring to the drawings, Fig. 1 is a diagrammatical front view of a safe door and its vestibule; Fig. 2 is a perspective view of a section of the door; Fig. 3 is a sectional view of a door incorporating a modified form of construction; Fig. 4 is a sectional view of a door incorporating another modified form of construction; and Figs. 5, 6, 7, 8, 9, 10 and 11 are each sectional views of one wall of a vestibule, and each shows a different modified construction embodying our inven-

tion. Similar reference characters refer to similar parts throughout the several views of the drawings.

Referring to the drawings, there is shown in Fig. 1 a safe door 1 and its vestibule 2, the door being supported by the usual crane hinge 3. As shown in Fig. 2, a metal section 4, constituting the body of the door and including the front and jamb portions and outer bolt frames 5, is formed with a central cavity. The outside of this may or may not be a continuation of the inside line of the outer bolt frames 5. The central cavity ends in an undercut groove or recess portion 6. A plate or section 7 constructed of material having special characteristics, such as torch-resistance or drill-resistance, is attached to an inner metallic section 8, with which the inside line of bolt frames 9 may or may not be cast solid. The plates or sections 7 and 8 are rigidly locked together by means of interlocking dovetailed tongue and groove connection 10. A similar connection may be had between sections 7 and 4. In assembling the construction strip-like sections 11 of the special material are placed within the undercut grooves 6. Then the sections 7 and 8 are fitted into the central cavity in the door body section and the parts are secured and locked firmly together by means of pins 12 which penetrate the jamb portions of section 4 and enter the section or plate 8. These pins can be a drive fit or a wedge fit, and, if desired, may be constructed of metal similar to that employed for the section 7 and 11. The number and diameter of the pins 12 may be varied as circumstances dictate and in accordance with the strength required. The bolts 13 which penetrate the bolt frames 5 and 9 may also serve to hold the sections 7 and 8 against movement with respect to the body section 4. Preferably the section 7 has a beveled fit, as at 14, against the side strips 11, to prevent the section 7 from being moved outwardly bodily in case of a corresponding portion of the front door becoming removed in consequence of an attack upon the structure. The outer sides of strips 11 may be beveled as shown to make their removal more difficult.

If desired, the jamb edge portions of the section 4 may be machined out to provide one or more grooves, such as 15 and 16, in which additional continuous pieces, such as

17 and 18, of metal having the desired special characteristics may be fitted. These sections 17 and 18 are preferably continuous around the edges of the door and one of 5 these sections, such as 17, may be so located that the location of the pins 12 are covered and concealed thereby, and access to all the pins cannot be had unless the entire section 17 be removed. Preferably the sections of 10 the material having the special characteristics are of such size and are so located that the sections will be in overlapping relation across the door, and thereby creating a construction which incorporates material 15 having special characteristics extending extensively across the area of the door in the plane thereof, extending from one edge of the door to the other and from the top to the bottom. Preferably the body 4 of the 20 door is so machined for the strips 17 and 18 that the grooves therefor are slightly undercut and thus provides overlapping edges such as 19 and 19' which tend to hold the strips 17 and 18 against displacement and 25 removal from the grooves.

The modified form of construction shown in Fig. 3 is similar to that shown and described in connection with Fig. 2 except that the central cavity in the body section 20 is 30 not undercut and is not provided with outside grooves or recesses for outside strips of metal having special characteristics. A section or plate 21 of metal having special characteristics, such as being resistant to drill 35 or torch, is joined by means of a dovetailed tongue and groove connection 22 to a section 23 and these joined sections are fitted in the cavity of the section 20. Pins 24 extending through the jamb portions of the section 20 40 and into the sections 23 hold the sections 21 and 23 in the cavity. The outside ends of these pins 24 are preferably so finished that their location cannot be determined on the edges of the door.

45 The construction illustrated in Fig. 4 is similar to that illustrated in Fig. 3 except that the cavity in the body section 25 is undercut in a manner similar to that shown in Fig. 2 and is provided with a continuous 50 outside groove 26 similar to the groove 16 shown in Fig. 2. This construction includes pieces 27 of material having special characteristics located in the undercut grooves, a central section 28 of material having special 55 characteristics, and a continuous strip of similar material 29 located in the groove 26 provided therefor. Pins 30 extend through the jamb portions of the casting 25 and into the metal section 31, to which section 28 is 60 joined by dovetailed tongue and groove connection, as at 10', which holds the construction rigidly and firmly assembled.

Material having similar special characteristics may be incorporated satisfactorily in 65 the vestibule wal' 2 of the safe in many

ways to prevent penetration of the walls by means of drills or torches, or the like. For instance, as shown in Fig. 5, the wall 32 may have one or more grooves, such as 33 and 34, machined therein and strips of material having the desired special characteristics may be fitted into these grooves, as at 70 35, 36, and 37. As shown in Fig. 6, by extending a portion of the vestibule wall 32' outwardly, as at 38, one of the recesses, such as 39, may be extended in the same direction 75 to receive larger strips 40 of material having the special characteristics. Instead of extending the recesses for the strips of special material from the jamb, a cavity for 80 strips of this material may be extended from the inner side of the vestibule wall, as at 41. This cavity is preferably tapered forwardly and the strip 42 of material having the special characteristics is similarly tapered so that when it is fitted in the forward end of the cavity it may not be removed forwardly therefrom in case the end of the wall is destroyed in an attack upon the structure. The interior walls of the safe, 85 such as 43, may extend into this cavity and abut the strip 42 from behind to prevent rearward movement thereof. Suitable filling 45, such as concrete or the like, may be employed to fill the space between the front 90 wall 46 of the safe and the strip 42. As shown in Fig. 8, the outer side of the tapered cavity 47 may be the continuation of the safe side plate 48, which extends the length 95 of this cavity. A strip of drill proof or torch resistant material 49 may be located in the forward end of the cavity 47 and may be attached to a metallic section 50 which is arranged to fill the rear portion of the cavity. As shown in Fig. 9, the tapered cavity 100 51 may have fitted therein a section 52 of material having special characteristics which is attached to another section 53, and these sections may be held in the cavity by 105 means of pins 54 which extend through the 110 vestibule wall and into the section 53. As shown in Fig. 10, the edge of the vestibule wall may be machined out along the line of the pins 54' to form grooves in which material having special characteristics, such as 115 55, may be located to conceal the location of the pins 54' and to prevent their removal. If desired, a groove 56 filled by a strip 57 of material having special characteristics 120 may be formed in the vestibule wall so as to extend into the wall from the side opposite the jamb. In Fig. 11 there is illustrated a construction in which the vestibule wall 58 has a tapered cavity 59 which is straight on one side. The side wall 60 of the safe extends along this straight side for the full length of the cavity and the remainder of the cavity is completely filled by a suitably 125 tapered piece or section 61 of material having the desired special characteristics. 130

As many changes could be made in the above construction and many different embodiments of our invention could be made without departing from the scope thereof, 5 it is intended that all matter contained in the above description or shown in the accompanying drawings be interpreted as illustrative and not in a limiting sense.

What we claim is:—

10 1. In safe construction, a door comprising, in combination, two interfitting metallic sections, one constituting the front and jamb edges of the door and the other constituting the rear wall of the door, a section 15 of material having special characteristics, resistant to drill or torch, fitted into the interior of the door between said sections, and means, including pins extending through the jamb edge portions of the door and into the 20 rear wall section, for maintaining said parts in assembled relation.

2. In safe construction, a door comprising, in combination, two interfitting metallic sections, one constituting the front and 25 jamb edges of the door and the other constituting the rear wall of the door, a section of material having special characteristics, resistant to drill or torch, fitted into the interior of the door between said sections, means, including pins extending 30 through the jamb edge portions of the door and into the rear wall section, for maintaining said parts in assembled relation, a groove on the exterior side of the jamb edge 35 portion, and a strip of metal fitted in said groove.

3. In safe construction, a door comprising, in combination, two interfitting metallic sections, one constituting the front and 40 jamb edges of the door and the other constituting the rear wall of the door, a section of material having special characteristics, resistant to drill or torch, fitted into the interior of the door between said sections, means, including pins extending through 45 the jamb edge portions of the door and into the rear wall section, for maintaining said part in assembled relation, a groove on the exterior side of the jamb edge portions at 50 the location of said pins thereon, and a strip of metal fitted in said groove and covering the exterior ends of said pins.

4. In safe construction, a door comprising 55 in combination, two interfitting metallic sections, one constituting the front and jamb edges of the door and the other constituting the rear wall of the door, a section of material having special characteristics, resistant to drill or torch, fitted into the interior of the door between said sections, means, including pins extending through the jamb edge portions of the door and into the rear wall section, for maintaining said parts in assembled relation, a plurality of 60 grooves on the exterior side of the jamb 65

edge portion, and strips of material having special characteristics, resistant to drill or torch, fitted into said grooves, the size and location of such grooves and fitted strips in relation to said interior fitted section of material being such that material having said special characteristics extends across the area of the door, in the plane thereof, and substantially coextensive therewith.

5. In safe construction, a door comprising, 70 in combination, a body section having a central cavity including undercut recess portions toward the front of the door, strips of material fitted into said undercut recess portions, a section of material fitted into the front portion of said cavity and having a beveled surface engagement with said strips, the material of said section and strips having special characteristics, resistant to drill or torch, a rear section fitted into said cavity 75 at the rear of said section and having a dovetailed tongue and groove connection therewith, and pins penetrating said body section and extending into said rear section, maintaining said parts in assembled relation. 80

6. In safe construction, a door comprising, 85 in combination, a body section having a central cavity including undercut recess portions toward the front of the door, strips of material fitted into said undercut recess portions, a section of material fitted into the front portion of said cavity and having a beveled surface engagement with said strips, the material of said section and strips having special characteristics, resistant to drill or torch, a rear section fitted into said cavity 90 at the rear of said section and having a dovetailed tongue and groove connection therewith, pins extending into said body casting and into said rear casting, 95 maintaining said parts in assembled relation, outer bolt frames on said body section, and inner bolt frames on said rear section, the sides of the said cavity in the body section being in alignment with the inner sides 100 of said outer bolt frames. 105

7. In safe construction, a door comprising, 110 in combination, two interfitting metallic sections, one constituting the front and jamb edges of the door and the other constituting the rear wall of the door, a section of material fitted into the interior of the door between said sections, a groove about the exterior side of the jamb edge of the door, and a strip of metal fitted in said groove. 115

8. In safe construction, a door comprising, 120 in combination, two interfitting metallic sections, one constituting the front and jamb edges of the door and the other constituting the rear wall of the door, a section of material having special characteristics, resistant to drill or torch, fitted into the interior of the door between said sections, a groove about the exterior side of the jamb edge of the door, and a strip of material 125

having special characteristics, resistant to drill or torch, fitted into said groove.

9. In safe construction, a door comprising in combination, two interfitting metallic sections, one constituting the front and jamb edges of the door and the other constituting the rear wall of the door, a section of material having special characteristics, resistant to drill or torch, fitted into the interior 10 of the door between said sections, a plurality of grooves on the exterior side of the jamb edge portion, and strips of material having special characteristics, resistant to drill or torch, fitted into said grooves, the 15 size and location of such grooves and fitted strips in relation to said interior fitted section of material being such that material having said special characteristics extends across the area of the door, in the plane 20 thereof, and substantially coextensive therewith.

10. In safe construction, a door comprising, in combination, a body section having a central cavity including undercut recess 25 portions toward the front of the door, strips of material fitted into said undercut recess portions, a section of material fitted into the front portion of said cavity and having a beveled surface engagement with said 30 strips, the material of said section and strips having special characteristics, resistant to drill or torch, a rear section fitted into said cavity at the rear of said section and having a dovetailed tongue and groove connection therewith.

11. In safe construction, a vestibule wall comprising, in combination, a wall section having a tapering groove extending from the rear side thereof, a similarly tapered strip of material having special characteristics, resistant to torch or drill, fitted in the forward end of said groove, a section of another material fitted in the groove at the rear of said strip, and pins extending into said rear section and into said wall 45 section, maintaining said parts in assembled relation.

12. In safe construction, a vestibule wall comprising, in combination, a wall section having a tapering groove extending from 50 the rear side thereof, a similarly tapered strip of material having special characteristics, resistant to torch or drill, fitted in the forward end of said groove, a section of another material fitted in the groove at the 55 rear of said strip, pins extending into said rear section and said wall casting, maintaining said parts in assembled relation, another groove in said wall section, and another section of material having special 60 characteristics, resistant to drill or torch, fitted into said groove, the location of said groove and strip being at the location of said pins and said strip covering the exterior ends of said pins.

This specification signed this 30th day of January, 1924.

GUSTAVE M. GOLDSMITH.
CARL BARTELS.
